REFRIGERATING APPARATUS

Don E. Dasher, Dayton, Ohio, assignor to General Motors Corporation, Dayton, Ohio, a corporation of Delaware

Application March 9, 1939, Serial No. 260,789

6 Claims. (Cl. 62—127)

This invention relates to refrigerating apparatus and more particularly to liquid control means for mechanical and absorption type refrigerating system.

Restrictors are now used extensively in mechanical systems for different applications, particularly household refrigerators. The restrictors now being used are inflexible. They can be designed to provide the best efficiency only under a single condition of load. For example, if the 10 restrictor is designed to provide the best efficiency when the room temperature is 110°, it will be much less satisfactory and less efficient for lower room temperatures, such as 70°. If the restrictor is designed for best efficiency in a 90° room it will be less satisfactory and less efficient in a 110° or a 70° room. Restrictors have been designed which are automatically adjustable, but I find that these automatically adjustable types are not sufficiently accurate and are not sufficiently 20 reliable mechanically to justify their use.

It is therefore an object of my invention to provide a restrictor which is simple mechanically and thoroughly reliable and which will accommodate its flow according to varying room temperatures and load conditions to secure a satisfactory flow of refrigerant and refrigerating efficiency over a relatively wide range.

It is another object of my invention to provide a simple restrictor which will reduce the cross-sectional area as the pressure differential increases.

The use of restrictors in absorption systems has been negligible. This is largely due to the fact that in the intermittent absorption type of refrigeration, which requires a pressure reducing device, it is desired to provide a restriction to the flow of liquid in one direction and to permit a free flow of evaporated refrigerant in the opposite direction when the cycle changes. Heretofore, no restrictor so far as I am aware has accomplished this, but it has been necessary to provide a by-pass with a check valve or some other scheme in order to do this.

It is therefore another object of my invention to provide a restrictor which will permit free flow of refrigerant in one direction and yet provide a properly restricted flow in the opposite direction.

It is another object of my invention to provide 50 a restrictor in which the refrigerant is forced to pass throughout the passages in the restrictor in one direction while in the opposite direction it is permitted to flow freely without passing through the restrictor passages.

It is another object of my invention to provide a restrictor comprising a member having a grooved face and a second member capable of fitting against or being withdrawn from the grooved face to close or open the grooves to provide a restricted or free flow of fluid through the restrictor.

Further objects and advantages of the present invention will be apparent from the following description, reference being had to the accompanying drawing, wherein a preferred form of the present invention is clearly shown.

In the drawing:

Fig. 1 is a sectional view of a restrictor embodying my invention;

Fig. 2 is a view of the grooved face of one of the members of the restrictor shown in Fig. 1;

Fig. 3 shows the restrictor applied to a mechanical refrigerating system;

Fig. 4 shows an enlarged sectional view of a fragmentary portion of the restrictor passages;

Fig. 5 shows two of the restrictors applied to a twin generator-absorber type of refrigerating system; and

Fig. 6 is an enlarged fragmentary sectional view of a modified cooperating member.

Briefly, there is shown a restrictor comprising a member having a grooved face which is normally held in engagement with a member of a rubber-like material by the pressure differential existing between the inlet and the outlet of the restrictor. The refrigerant enters spiral grooves at the outside of the grooved face and passes through to the outlet provided at the center. As the pressure differential increases the grooved member is pressed more tightly into the member of rubber-like material so that the cross-sectional area of the spiral groove is reduced. When the restrictor is used in a mechanical refrigerating system the refrigerant always flows in one direction, but when used in an intermittent absorption type system the pressure differential is reversed and the grooved member is pushed away from the rubber-like member so that the refrigerant can readily flow in the opposite direction.

Referring to the drawing and more particularly to Fig. 3 there is shown diagrammatically a compression type of refrigerating system including a compressor 20 driven by an electric motor 22 for compressing the refrigerant and forwarding the compressed refrigerant to a condenser 24 where the compressed refrigerant is liquefied and collected in a receiver 26. From the receiver 26 the liquid refrigerant is for-

warded through the supply conduit 28 to a restrictor 30 which controls the flow of refrigerant into the evaporating means 32 which is located within the compartment 34 indicated diagrammatically by dot and dash lines. The refrigerant evaporates within the evaporating means 32 under reduced pressures to cool the compartment 34 and is returned to the compressor through the return conduit 36. The operation of the motor-compressor unit is controlled by a thermostat switch 38 which is provided with a thermostat control bulb 40 mounted upon the evaporating means 32.

Heretofore restrictors which have been used were formed either of a considerable length of small bore tubing or formed from a threaded metal restrictor. By employing an orifice of sufficient length and proper cross-section a fairly satisfactory form of control for mechanical refrigerating systems is provided in this way. Its simplicity and lack of moving parts is admirable. However, it is found that if the restrictor is designed to provide the best efficiency under heavy load conditions, such as occur when the room temperature is 110° F. that the efficiency is comparatively poor at lower room temperatures at which most of the operation is performed. For example, if the restrictor is designed to provide 90 pounds head pressure and 12 inches back pressure under 110° room temperature conditions, the restrictor would be too small for efficient 70° room temperature operation and the back pressure would drop to 18 inches and the head pressure would fall to 50 pounds. By operating at 18 inches back pressure the compressor would operate for a longer time at a lesser efficiency and since the thermostat switch was not set at such a low temperature, the extremely low back pressure serves no useful purpose.

In order to provide more efficient operation throughout the range it is desired to keep the back pressure substantially constant. For example, if the head pressure is 90 pounds and the back pressure is 12 inches in a 110° room, it is desired to keep the back pressure at about 12 inches in the 70° room. Since the compressor would compress gas more rapidly at this back pressure than at the 18 inch back pressure the condenser pressure would probably rise to about 60 pounds. However, the restrictors heretofore used or proposed have not accomplished this.

In order to provide a restrictor which will provide such results I have evolved the restrictor shown in Figs. 1 and 2. In this restrictor, generally designated by the reference character 30, there is provided a cup-shaped member 50 which is connected to the liquid supply conduit 28 through a bossed central aperture 52. The cup-shaped member 50 is closed at the other end by a cap member 54 which is threaded into the open end of the cup-shaped member 50. The cap member 54 is provided with a bossed aperture 56 which connects to the inlet of the evaporating means 32. Within the chamber provided in the cup-shaped member 50 is a disk 58 of a suitable rubber-like material having an aperture registering with the bossed aperture 56 in the member 54. This disk shaped member 58 may be formed of ordinary rubber properly compounded to give the desired softness and elasticity or it may be made of some other other rubber-like material properly compounded to give the desired characteristics. For example, the disk may be compounded from such materials

known under the trade names of "Duprene," "Neoprene" and "Thiokol" properly compounded to give satisfactory characteristics. Held pressed against the face of the disk 58 by the pressure differential upon the restrictor is a cylindrical metal block 60 having a face provided with a spiral groove 62 which extends spirally inwardly from the outer edge of the block 60 and a recess 64 located in the center of the grooved face of the block. Between the adjacent convolutions of the groove 62 there is provided a flat spiral land portion 66 which rests against the face of the rubber-like disk member 58 held against the inner wall of the cap member 54. If desired this disk 58 may be cemented or vulcanized to this inner face of the cap member 54.

The restrictor 30 is preferably positioned so that the cylindrical metal block 60 rests by gravity upon the rubber-like disk 58. Where this arrangement is not desired, some means such as a spring or stop means may be used to hold the block 60 against the disk 58. Also if desired, the block 60 may fit the interior of the member 50 with sufficient tightness that the pressure differential upon it will be sufficient to move and to hold it in engagement with the rubber-like disk 58.

Since the rubber-like disk 58 is soft and elastic the greater the pressure differential existing upon the block 60, the greater will be the pressure forcing the land or flats 66 of the grooved face of the block into the rubber-like material 58. The forcing of the grooved face into the rubber-like material 58 will cause the rubber-like material of the member 58 to flow slightly into the groove 62. Thus, the greater the pressure differential, the more rubber-like material will be forced into the groove 62 to provide a greater reduction in the cross-sectional area of the orifice which is provided within the V-shaped grooves 62. It will be apparent that the softer the material of the rubber-like disk 68 the more readily the material of the disk 58 will be forced into the groove 62 to reduce the cross-sectional area of the orifice. Thus by controlling the softness and elasticity of the disk 58, the amount of change in the cross-sectional area with a change in pressure can thereby be controlled. Instead of the rubber-like materials mentioned above other materials which are somewhat elastic and which can flow into the grooves may be used. For example, leather and other materials having similar properties might be used for this purpose.

It is also possible to vary the control thus provided by varying the shape of the grooves or by varying the width of the land or flats 66 and varying the depth of the grooves and by varying the length of the grooves to change the characteristics of the control provided by the forcing of the material of the disk 58 into the grooves. For example, it is evident that if the area of the flats 66 is reduced, the disk member 58 will offer less resistance to the movement of the flats into its surface and thus more of the material of the disk 58 will be forced into the grooves 62. Likewise if the included angle of the groove 62 is increased, the material of the disk 58 will occupy a greater proportion of the cross-sectional area of the groove. It will also be evident that if the grooves are made square or half round in cross-section, the amount of material of the disk 58 which is pushed into the groove will provide a smaller percentage reduction in cross-sectional area of the orifice. Thus

it will be seen that this restrictor makes it possible to control the cross-sectional area of the orifice according to pressure differences and that such variation in cross-sectional area can be controlled over comparatively wide limits, with a comparatively wide difference in ratio of the pressure to the restriction of the orifice.

This restrictor is also advantageous for use in an intermittent absorption type refrigeration system. In Fig. 5 one of the restrictors is used at each end of the evaporator in a twin generator type of absorption refrigerating system, which includes the generators 120 and 122 which are connected to the condensers 124 and 126 which in turn are connected to the restrictors 128 and 130 made like the restrictor 30. Connected between the restrictors is an evaporating means 132 formed of a coil of tubing which is wrapped around a sleeve and located within the compartment 134 which is to be cooled.

The generators 120 and 122 are heated alternately by the gas burners 136 and 138 which are lighted by individual pilot lights 140 and 142 connected directly to the gas supply line 144. Gas is supplied alternately to the burners 136 and 138 according to the position of the two-way snap acting valve mechanism generally designated by the reference character 146. This two-way snap acting valve mechanism 146 is operated according to the temperatures of the thermostat bulbs 148 and 150 which are located in heat exchange relation with the generators 120 and 122. The thermostat bulbs 148 and 150 are connected to the bellows 152 and 154 to operate the two-way snap acting valve 156.

As shown in Fig. 5, the generator 122 is being heated so that refrigerant is driven from this generator-absorber to the condenser 126 where the refrigerant is condensed and passes through the restrictor 130 into the evaporating means 132 where it evaporates under reduced pressure and flows freely through the restrictor 128 and the condenser 124 to the absorber 120 which is being cooled by air which contacts with and cools its finned surfaces. The rate of heating of the generator-absorbers is controlled by a thermostat valve 158 located in the gas supply pipe which leads to the snap acting valve mechanism 146. This thermostatic valve 158 is controlled according to the temperature and the thermostat bulb 160 located in heat exchange relationship to the evaporating means 132. Thus the temperature of the evaporating means controls the rate of gas supply to the burner which is operated.

It will be seen that the restrictor 130 is like the restrictor shown in Fig. 1. In this case the flow is from the condenser to the evaporator just as it is in Fig. 1 and the effect is the same, since the flow in restrictor 30 is from an inlet corresponding to the passage 52 in Fig. 1 to the outlet which corresponds to the passage 56 also in Fig. 1. Thus the restrictor 130 in the cycle shown will act just like the restrictor 30 in Fig. 3.

The restrictor 128 is positioned on the drawing just as the restrictor 30 is positioned in Fig. 1. However, the flow through the restrictor 128 during this cycle is in the direction opposite to the flow through restrictor 30 in Fig. 1. This reversed flow of course reverses the pressure differential upon the restrictor and causes the cylindrical block, provided in the restrictor 128, corresponding to the cylindrical block 60 by Fig. 1, to be lifted or moved away from the disk of rubber-like material corresponding to the disk

58 of Fig. 1. This will allow the evaporated refrigerant from the evaporator 132 to flow freely through the restrictor 128 and the condenser 124 to the absorber 120. This is of course very desirable since any restriction at this point in this cycle will reduce the efficiency of absorption in the absorber 120.

When the refrigerant within the generator 122 has been substantially driven off, the thermostat 150 will be heated sufficiently to cause the valve 146 to operate to change the supply of gas from the burner 138 to the burner 136. This will reverse the flow of refrigerant through the system and cause the restrictor 128 to restrict the flow in the manner of the restrictor 30 in Fig. 3, while the restrictor 130 will permit gas to escape freely from the evaporating means 132 to the condenser 126 and the generator-absorber 122. When the cylindrical block is lifted away from the disk of rubber-like material the gas will flow freely without passing through the grooves in the face of the block to an appreciable extent and will pass around the edges of the block to the other side of the block where it can flow freely into the condenser and generator-absorber which is absorbing at that time. Thus, this improved form of restrictor has the advantages of extreme simplicity and yet is capable of being used to great advantage upon either compression systems or absorption refrigerating systems.

In Fig. 6 there is shown a modified form in which an extremely thin metal disk 259 covers the working surface of the rubber-like disk 258. If desired the thin metal disk 259 may be vulcanized or otherwise bonded to the surface of the rubber-like disk 258. The thin metal disk may be of brass or copper or other suitable metal about 0.003 inch or 0.005 inch in thickness. This thin metal will protect the surface of the rubber-like disk 258 and will reduce the amount of reduction in area of the grooves in the member 60. This construction is particularly useful where higher pressure differentials are required.

While the form of embodiment of the invention as herein disclosed, constitutes a preferred form, it is to be understood that other forms might be adopted, all coming within the scope of the claims which follow.

What is claimed is as follows:

1. A restrictor comprising a first member and a second member, one of said members being provided with a substantially flat portion and the other with a spiral groove in a portion of its surface, said spiral grooved portion being in contact with the flat portion of the other member to form an elongated passage of great length in proportion to its cross-sectional area, said spiral groove being provided with an end adjacent the outer edge and an end adjacent the center of one of said members, one of said ends forming the inlet to the groove and the other the outlet, one of said members being freely movable away from the other, said movable member and the other member being subject to the pressure of a fluid flowing through the groove to separate the members.

2. A restrictor comprising a member having a yielding elastic surface and a second member, one of said members being provided with a land and a groove in a portion of its surface, said land of said grooved portion being in contact with a portion of the other member to form a passage between said members, said passage be-

ing provided with an inlet and an outlet, one of said members being freely movable away from the other to separate their adjacent surfaces, said movable member being subject to the pressure of the fluid flowing through the groove providing a separating force to separate the adjacent surfaces of the members when the fluid flows in one direction and provided with pressure means acting in an opposite direction to hold the members together when the fluid flows in an opposite direction.

3. Refrigerating apparatus including evaporating means and liquefying means, restrictor means forming an elongated passage of great length in proportion to its cross sectional area for controlling the flow of fluid between the liquefying means and the evaporating means, and means responsive to an increase in pressure in the liquefying means for reducing the cross-sectional area throughout the greater portion of 20 said passage.

4. A restrictor comprising a first member having a yielding elastic surface, a second member provided with a surface in contact with the elastic surface of said first member, one of said contacting surfaces being in the form of a land holding adjacent portions of the surfaces adjoining said land away from each other to provide a passage between the adjacent surfaces of said members, means for connecting the inlet and outlet of said restrictor to opposite ends of said passage, and means for continuously sub-

jecting one of said members to a yielding force tending to hold the contacting surfaces of said members in engagement, said one member being freely movable under the influence of said yielding force.

5. A restrictor comprising a first member having a yielding elastic surface, a second member provided with a portion of its surface in contact with a portion of said elastic surface, one 10 of said surfaces being provided with a land and a recessed portion, said recessed portion providing a passage having an inlet and an outlet, and means for subjecting one of said members to a yielding force derived from the pressure of a fluid flowing through said passage for applying a contact pressure between said contacting surfaces for deforming said elastic surface to change the size of the passage.

6. A restrictor comprising a first member having a yielding elastic surface, a second member provided with a portion of its surface in contact with a portion of said elastic surface, one 25 of said surfaces being provided with a land and a recessed portion, said recessed portion providing a passage having an inlet and an outlet, one of said members being provided with means for applying a contact pressure between said contacting surfaces including means for applying a force to one of said members derived 30 from a fluid pressure outside said passage.

DON E. DASHER.
